(57) **CLAIM**

I claim the ornamental design for a shelf-mounting bracket, as shown and described.

DESCRIPTION

FIG. 1 is a top view of a shelf-mounting bracket, showing our new design.

FIG. 2 is a bottom view of the claimed design.

FIG. 3 is a right side view of the claimed design.

FIG. 4 is a left side view of the claimed design.

FIG. 5 is a front view of the claimed design.

FIG. 6 is a rear view of the claimed design; and,

FIG. 7 is a perspective view of the claimed design.
